CONTAINER HOLDER

Antonio Fransosi, Providence, R. I.

Application August 16, 1933. Serial No. 685,378

2 Claims. (Cl. 248—20)

This invention relates to a holding device for a container, more particularly a bottle; and has for one of its objects the provision of means by which this holder may be readily manipulated for placing the container into and taking the same from its mounted position.

Another object of the invention is the provision of a holder which may be moved from one position to another without removal and detachment of any of the parts thereof, thereby avoiding accidental dropping or misplacing of any of the parts which may interfere with the proper functioning and assembling of the holder for use.

Another object of the invention is the provision of a support for the holder which will be symmetrical and so positioned that smaller and less expensive rods may be used while providing a better support and one which serves to guard the container to some extent against injury.

A further object of the invention is the provision of a container holder which will be less expensive to manufacture and yet one which will function more efficiently than those which are known to me at the present time.

With these and other objects in view, the invention consists of certain novel features of construction, as will be more fully described, and particularly pointed out in the appended claims.

In the accompanying drawing:—

Fig. 1 is a perspective view of a standard provided with my improved holding device and showing a bottle mounted in position.

Fig. 2 is a side elevation of the holding device with the bottom part of the standard broken away.

Fig. 3 is a view similar to Fig. 2 showing a holding device as raised to a position to permit removal of the bottle.

Fig. 4 is a perspective view of a band-shaped holder.

Fig. 5 is a perspective view showing the band-shaped holder with the front member swung 45 to permit removal of the bottle.

Fig. 6 is a sectional view thru the holder as mounted upon the upper end of one of the support rods.

Fig. 7 is a perspective view of one portion of 50 the holding device equipped with means for mounting it on differently positioned rods.

Fig. 8 is a perspective view of one member of the embracing element equipped with means for mounting it upon a single upright rod.

In the use of oil burners, it is usual to provide

a reservoir for oil, such as a bottle, which will be supported at the proper height to supply the oil burner thru some suitable conduit and as it is necessary to frequently remove and fill this bottle to replenish the supply of oil as used and 60 in order that the bottle may be removed, it is usual to provide some sort of detachable clamping device for the upper end of the bottle, and for such clamps there have been used partial bands which have some resiliency to spread and

then contract about the bottle, while others embrace the bottle and have detachable parts to swing open as a door in the plane of the clamping device. This latter requires an additional part, such as a locking pin, which may become lost or 70 misplaced to the annoyance of the user and in order that there may be positive holding by a complete encircling band and yet one which may be readily manipulated for removal of the bottle,

I have divided the band into two members and 75 pivoted them together at generally diametrically opposite points so that when in holding position they will be in the same plane but may be moved at right angles with one member above the end of the bottle to permit removal of the bottle

while this member may be swung down so that 80 both of the semicircular members will be in the same plane to embrace the bottle, and in order that this band may be securely supported I have provided two rods extending upwardly from dia-

metrically opposite points which securely support 85 this band in position and also guard the bottle from being struck and serve to enhance the ornamental appearance of the standard as well as to increase its efficiency and strength; and the

following is a detailed description of the present embodiment of this invention illustrating the preferred means by which these advantageous results may be accomplished:—

With reference to the drawing, I have shown 95

at 10 a pedestal standard from which there arises an adjustable post 11 supporting an oil chamber 12 which may be of any suitable configuration altho I have shown one of diamond shape in this instance. A cover 13 extends across this chamber and is provided with an opening to receive the neck 15 of the bottle 16, there being suitable controls provided in the chamber to govern the flow

of the liquid from the bottle. At diametrically opposite points bosses 17 are provided which support the lower ends of the upright rods 18, extending along diametrically opposite sides of the bottle 16. These rods are reduced in diameter

at their upper ends, as at 20, to provide shoulders 21 and are threaded as at 19, see Fig. 6. 105

110

The holding device for the upper end of the bottle consists of an element embracing the bottle and is formed of two members 22 and 23. The member 22 is substantially semi-circular and is rolled at its ends 24 to provide eyes 25 to receive the reduced upper ends 20 of the rods 18 and is held in place on these reduced upper ends against the shoulders 21 by nuts 26 engaging the threaded ends of the rods. These nuts may be provided with ornaments 27 to enhance the appearance of the structure, if desired.

In some instance, it is desirable to thread the lower end of the rods 18 and I will in that case mount a similar ornamental nut such as 26 and 27 upon this lower end, as illustrated in Figs. 2 and 3.

The member 23 is also semi-circular in shape and its ends fit just inside of the ends of the member 22. Pivots 28 extend thru these overlapping portions above the centers of the bands and at a point along the upper edge of each of the members so as to provide an eccentric pivot. This member 23 is also provided with a handle 30 by which the member 23 may be moved from the position illustrated in Figs. 1, 2 and 4 to the position illustrated in Figs. 3 and 5.

When in the securing or working position illustrated in Figs. 1 and 2, the bottle is encircled by the embracing element and when the member 23 is in the position illustrated in Figs. 3 and 5, the upper end of the bottle is free to be removed from the back member 22 to be filled and replaced or replaced by a different bottle, when desired.

This swinging of the part 23 about its pivot may be accomplished without the removal or detachment of any of the parts and thus as the entire assembly remains intact regardless of the position to which the members are moved there is no opportunity for misplacing or losing any of the parts.

In some instances, it is desirable to provide the

rods at a point other than at the ends of the band and thus I have provided ears 31 and 32, as illustrated in Fig. 7, at points other than at diametrically opposite points on the embracing band for the reception of the rods placed in such position.

In other instances, a single rod may be used and a resilient pair of jaws 33 and 34 provided, each having an opening thru which a bolt and nut may extend to contact them, in order that my improved band may be mounted upon a single rod.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. A container holder comprising an embracing band element having two members pivoted together at substantially diametrically opposite points to swing from a common plane to planes at substantially right angles to each other to selectively embrace or permit removal of the container, and means for supporting one of said members in a position adjacent the upper end portion of the container.

2. A container holder comprising an embracing band element having two members pivoted together at substantially diametrically opposite points to swing from a common plane to planes at substantially right angles to each other to selectively embrace or permit removal of the container, and spaced supports secured to one of said members adjacent the pivotal points for supporting the members in position adjacent the upper end portion of the container.
